UNITED STATES PATENT OFFICE

JOSEPH PHILIAS TETREAULT, OF PROVIDENCE, RHODE ISLAND

REINFORCED DENTURE

Application filed February 12, 1929. Serial No. 339,481.

This invention relates to the class of dentistry and pertains particularly to improvements in the construction of dentures.

The primary object of this invention is to provide, in a manner as hereinafter set forth, a means for improving the construction of dentures, more particularly those formed of vulcanized rubber or similar material whereby the same may be produced of lighter weight and thinner body construction, and at the same time of greater strength than the vulcanized rubber dentures of the type at present in use.

As is well known, in the manufacture of dentures at the present time vulcanized rubber, celluloid, bakelite and other phenol-resin products are extensively employed, first, because of the cheapness as compared with dentures constructed of metal such as gold, platinum and aluminum and second, because of the fact that these materials are more easily worked up to properly conform to the surface of a patient's mouth.

While the hard rubber and other products mentioned have certain advantages over metal, they have the disadvantages that they are extremely brittle and must therefore be made of extra heavy construction to withstand the strains placed thereon in the normal process of mastication.

The present invention aims to overcome the difficulties at present encountered in the use of hard rubber, etc., for dental plates by the provision of an especially constructed reenforcing wire which is designed to be molded into and about the edge of the material from which the denture is constructed, to give to the denture greater strength and resistance against the formation of cracks or breaks resulting from the strains placed thereon and to permit of the lighter construction of the denture.

I am, of course, aware that reenforcing has been used heretofore in the body of dentures but this reenforcing is such that the reduction of the thickness of the body is limited and at the same time it does not prevent the denture from cracking along the edges.

Another object of the present invention is to provide in addition to means for reenforc-

ing the edge of a denture, means whereby dentures employing clasps may be more strongly or ruggedly constructed to prevent their splitting, by the elimination of the usual pin carried by the clasp and ordinarily imbedded in the body of the denture. This anchoring pin of denture clasps frequently causes the denture to split whereas with the present reenforcing means no part of the clasp extends into the body of the denture to provide a means whereby strain might be placed thereon and effect the breaking of the denture.

The invention will be best understood from a consideration of the following detailed description taken in connection with the accompanying drawing forming a part of this specification, with the understanding, however, that the invention is not confined to any strict conformity with the showing of the drawing but may be changed or modified so long as such changes or modifications mark no material departure from the salient features of the invention as expressed in the appended claims.

In the drawing:

Figure 1 is a view of the under face of a denture reenforced in accordance with the present invention;

Figure 2 is a transverse sectional view of the denture shown in Figure 1, taken upon the line 2-2 of this figure;

Figure 3 is a detailed view of a portion of the reenforcing wire structure embodying the present invention;

Figure 4 is a view showing the application of the reenforcing wire to a clasp designed to maintain the denture in position.

Referring to the drawing in detail wherein like numerals of reference indicate corresponding parts throughout the several views, there is shown in Figure 1 a denture for use in the upper part of the mouth, the same being indicated by the numeral 1. This denture is shown as of the type having a palatal portion or plate 2 for maintaining artificial teeth in position at opposite sides of the jaw and carrying teeth engaging resilient clasps 3 for maintaining the denture in position instead of employing suction.

The free edges of this denture are reenforced by the structure embodying the present invention, this reenforcing structure being indicated generally by the numeral 4.

Upon referring to Figure 3, the denture edge reenforcing wire will be seen in detail, this wire constituting a base wire structure 5 and an attached filigree or gallery wire 6 which extends longitudinally of one side thereof. This gallery wire, while it may be of any appropriate design is preferably constructed as shown, that is to define a series of reversed dove-tail shaped bodies. This gallery wire portion 6 may be stamped from suitable material integrally with the base wire 5 or may be provided as a separate unit and applied thereto, in which case the side of the base wire 5 is flattened slightly to facilitate the proper securing of the gallery wire thereto.

As clearly shown in Figure 1, the reenforcing wire structure 4 is so molded in and along the edges of the denture that the base portion 5 will be exposed and form a border thereabout, whereas the material of which the denture is formed will flow into the recesses of the gallery wire and securely bond the reenforcing wire to the body of the denture.

As is shown in Figure 1 and indicated at points 7, the reenforcing wire may be soldered directly to the prongs of the clasp adjacent which its ends are positioned, thus further strengthening the denture by relieving the body thereof of a great deal of the strain normally imposed thereon by the clamps during mastication.

As shown in Figure 4, the present wire structure may also be advantageously employed in connection with denture clasps to replace the usual anchoring pins of clasps which are imbedded in the body of the denture. In this view, a small denture is shown as indicated by the numeral 8 and is provided at one end with the usual type of clasp 9, employing the anchoring pin 10 which extends into the body of vulcanized rubber or other material of which the denture may be constructed. At the other end of this denture is shown a clasp 11 constructed of the reenforcing material embodying the present invention, that portion of the body of the clasp contacting with the denture body, being provided with a section of gallery wire here indicated by the numeral 12 which is securely imbedded in the material of the denture and bonds or secures the clasp 11 thereto. It is, of course, clear that this denture 8, which for the effect of clearness has been shown without the addition thereto of artificial teeth, may be reenforced along its edges by the reenforcing material 4 and the ends of the reenforcing strips may be soldered to the clasps of the denture to further brace the same. This method of constructing the denture substantially amounts to the provision of an

elongated frame having a clasp at each end and filled in with a suitable material, such as vulcanized rubber or the like, in which the artificial teeth are imbedded.

From the foregoing description it will be readily apparent that dentures, particularly those of the type shown in Figure 1 where twisting strains are placed thereon during their use, constructed or reenforced with the bordering wire of the character herein described, may be very lightly molded without sacrificing strength, in fact, the strength of the denture as a whole is greatly increased by bordering the same with the wire 4.

While the present description has been confined to dentures of the type employing clasps for retaining them in position and a denture designed to fit across the roof of the mouth, it is, of course, to be understood that I do not wish to be limited in any manner to the use of the strengthening wire to dentures of these forms for it is apparent that the same may be as advantageously used in other types.

Having thus described my invention, what I claim is:

1. A reenforced denture, comprising a body of composition material, a resilient wire outlining certain edges of the body, and means forming a part of the wire designed to be imbedded in the material to bond the wire thereto.

2. A reenforcing lightweight denture, comprising a tooth carrying body of composition material, a resilient reenforcing wire bounding certain edges of the material, and a filigree structure formed along said reenforcing wire and designed to be imbedded in the denture composition to bond the wire thereto.

3. In a denture of composition material having retaining clasps, a reenforcing resilient element outlining certain edges of the denture and having the ends thereof secured to the clasps.

4. A reenforced denture, comprising a body of composition material, a resilient wire outlining certain edges of the body, and a relatively narrow body of filigree material secured along the inner edge of said wire and embedded in the composition material.

5. A resilient reenforcing material for dentures, comprising a solid wire like body and a relatively narrow body of filigree material secured to the wire like body and of a thickness substantially equal to the diameter thereof.

6. A resilient reenforcing wire for bordering the edges of dentures comprising a solid wire like portion and an attached wire like portion of filigree or grilled design, said latter portion being in thickness substantially equal to the first mentioned portion.

7. A reenforcing bordering wire of a resilient character for dentures, comprising a

wire like portion of solid formation and a portion attached to and extending longitudinally of the first mentioned portion, said attached portion comprising a flat, uniformly thick filigree member, in side elevation of a continuous, successively reversed dovetail character.

In testimony whereof I hereunto affix my signature.

10 JOSEPH PHILIAS TETREAULT.
